UNITED STATES PATENT OFFICE.

GEORGE NEVILLE SPERRY, OF BIRMINGHAM, ENGLAND.

SCREW-DOWN TAP OR COCK.

Application filed October 19, 1925, Serial No. 63,207, and in Great Britain March 31, 1925.

This invention relates to a new or improved screw-down tap or cock and refers to a tap or cock particularly adapted for controlling a domestic water supply.

In designing a water-tap or cock an important point has recently been to render the external surface of the tap as smooth and free from excrescences as possible to reduce to a minimum the labour in cleaning.

The object of my invention is to provide an improved construction of tap whereby a smooth exterior of pleasing appearance is obtained without impairing facility of access to the working parts of the tap for the adjustments which are necessary at intervals.

A further object is to combine with such a construction simple means whereby axial movement of the tap spindle to open or close the tap is effected by a purely rotary movement of the external operating handle or finger-piece so that no part of the spindle is visible even when the tap is open, and notwithstanding this the adjustment or repacking of the spindle gland can be effected while the tap is closed so that the water need not be turned off at the main.

My invention comprises an improved screw-down tap or cock in which the operating mechanism and spindle are wholly enclosed within a detachable sleeve secured to the tap body or head, and a handle or finger-piece rotatably secured in or upon the outer end of the sleeve has an axial aperture or recess within which the end of the tap spindle is free to slide, but is held against rotation relative thereto.

Thus rotation of the handle or finger-piece causes rotation of the spindle to retract or advance the valve in the usual manner and the axial movement of the spindle is accommodated by its sliding within the handle.

To obtain access to the working parts of the tap, which may be of any desired type, the valve is closed and the sleeve together with the handle or finger-piece is removed so that the spindle gland is exposed.

One convenient practical form of tap embodying the features of our invention has been illustrated by way of example in the accompanying drawings in which:—

Figure 1 is an external elevation of the tap.

Figure 2, is a sectional elevation.

Figure 3, is a section on an enlarged scale of the handle or finger-piece and the upper part of the sleeve.

Figure 4, is a section on an enlarged scale of the upper part of the sleeve showing an alternative method of rotatably securing the finger-piece thereto.

In these drawings *a* is the body of the tap which may be of any desired design, and *b* is the head which is screwed into the upper part of the body and carries the usual spindle *c* and valve *d*. The valve *d* is secured upon the lower end of the spindle in any convenient manner such as that illustrated in Fig. 2, and the lower part of the spindle has an external screw-thread engaging an internal thread in an axial recess *e* in the lower end of the head. The upper part of the spindle passes through the usual packing *f* and gland-nut *g* and its upper extremity *h* is of square or other angular cross-section.

It will be understood that these details are given as of a typical tap construction and are not essential to the present invention with the exception of the square or other angular cross-section of the upper end of the spindle.

The sleeve *j* within which the mechanism of the tap is enclosed is a hollow brass or other casting or pressing of the external outline indicated in Fig. 1, the lower end having the greatest diameter and being provided with an internal screw-thread by which it is adapted to be screwed on to a threaded flange *k* on the head or on to a similar flange on the body.

The exterior surface of the lower end of the sleeve may be arranged to be flush with the exterior surface of the body, but I prefer to provide an annular lip *l* so that the joint will always look neat even after having been made and broken a number of times.

The upper end of the sleeve is formed with a shoulder *m* above which projects a short cylindrical extension *n* of which the extremity is screw-threaded. The handle or finger-piece *o* has at its lower end an inturned flange *p* which is a smooth fit over the extension *n* and a nut or collar *q* is then screwed on to the extremity of the extension within the handle to secure the handle rotatably upon the sleeve. This nut is preferably sweated to the extension to prevent movement after fixing, or it may be riveted thereto or both sweated and riveted.

The connection between the handle and the tap spindle *c* is made by a tube *r* which has an axial aperture of square cross-section to receive the upper end of the spindle, and a

flange *s* at its upper end which is screw-threaded and is screwed into the axial opening in the handle, being subsequently locked in position by a pin *t* and/or by soldering. A leather, fibre, or other washer *u* is preferably placed between the lower face of the flange *s* and the nut *q* to ensure smooth working without slackness. The upper end of the opening in the handle is then closed by the usual china or other centre *u* indicating hot, cold, or any other desired information.

Alternatively, as shown in Fig. 4 the upper end of the sleeve is formed with an annular collar *w* which is adapted to encircle a depending cylindrical extension *x* of the handle so that a smooth working fit is obtained between the parts. The cylindrical extension *x* is of greater depth than the bearing surface of the collar, and the lower part is screwed to take a nut or like member *y* which engages beneath a shoulder *z* on the upper part of the sleeve.

After the parts have been assembled the nut *y* is preferably sweated and/or riveted in position so that the members are permanently secured together and relative axial displacement is impossible. As before, if it is found convenient washers may be placed between the bearing surfaces to ensure against slackness; or an annular projection may be provided on the upper edge of the sleeve collar, and this may work in a corresponding groove in the handle. The latter is hollowed out as shown in the Figure 4, in order to accommodate any form of china centre *v* and the interior of the depending portion *x* of the handle has an axial bore of square cross-section to receive the upper end of the spindle, and functions in exactly the same manner as the tube *r* of the previous example.

To remove the sleeve and handle in both of the constructions described, it is only necessary to unscrew the sleeve from the head, and, as the sleeve is free to rotate relative to the handle, the spindle is not disturbed but the handle will slide axially off the upper end of spindle.

Any required adjustments can then be made to the tap and the sleeve replaced with a minimum amount of trouble.

If it is desired to change the indication of the tap, for example from hot to cold, the sleeve and handle alone need be changed, and

this feature will be found of considerable advantage to dealers and plumbers.

55

I claim:—

1. A screw-down tap, comprising a body provided with a seating therein, a spindle carrying a valve head adapted to engage the seating, a gland in the upper end of the body through which the spindle passes, a hollow casing sleeve, enclosing but out of contact with the spindle and gland, detachably secured upon the body and normally stationary thereon but readily removable without disturbing the spindle or gland, a handle provided with a shank extending through the upper end of the sleeve and slidably keyed to the spindle, and a readily releasable connection between the handle and the sleeve permitting their independent relative rotation.

2. A screw-down tap, comprising a body provided with a seating therein, a spindle carrying a valve head adapted to engage the seating, a gland in the upper end of the body through which the spindle passes, a hollow casing sleeve, provided with an annular flange at its upper end, enclosing but out of contact with the spindle and gland, and detachably secured upon the body by a screw threaded connection at its lower end, and normally stationary on the body but readily removable therefrom without disturbing the spindle or gland, a handle provided with a shank extending through the upper end of the sleeve and slidably keyed to the spindle, and a nut establishing a readily releasable connection between the handle and the sleeve permitting their independent relative rotation.

75

3. In a device of the character described, the combination of a valve spindle, a hollow escutcheon having a central opening, a spindle actuating handle, a formation secured to the handle adapted to project into said central opening, means cooperating with said formation and escutcheon to maintain the handle and escutcheon in required relationship, but to permit the free rotation of the handle, and means effective between said formation and the spindle to lock the same together with respect to rotative movement, but to permit relative longitudinal movement.

90

In testimony whereof I affix my signature.

GEORGE NEVILLE SPERRY.
